LACQUERING MACHINE

Charles D. Dallas, Chicago, Ill., assignor to Revere
Copper & Brass Incorporated, Rome, N. Y., a
corporation of Maryland

Application August 26, 1931. Serial No. 559,464

10 Claims. (Cl. 91—55)

The invention relates to improvements in lacquering devices and has particular reference to devices of the character used in connection with cleaning and lacquering tubes or the like although the principles of the invention may be applied to the cleaning and lacquering of other articles than tubes.

It is well known to those familiar with the art that satisfactory lacquering requires that the surface to be lacquered should be thoroughly cleaned of dirt and grease particles before the lacquer is applied. The cleaning process requires the abrasion of the surface in the presence of a cleaning liquid suitable to cut or release dirt and grease. The surface must be dry when the lacquer is applied and in the usual practice, the time required for drying the article after cleaning prevents a continuous operation of cleaning and lacquering. Lacquering as heretofore practiced is accomplished either by submerging the article in a lacquer bath or by spraying the lacquer over the surface of the article. The dipping process involves waste and an uneven flow of the lacquer upon removal from the bath. In spraying, the atmosphere is filled with fumes involving a substantial waste of lacquer and the fume laden atmosphere renders any attempt to accelerate the drying of the freshly lacquered article by artificial means an extremely hazardous undertaking by reason of the possibilities of ignition and explosions. The handling of a freshly lacquered article must be postponed until the article is dry and as a result continuity of lacquering and handling is impossible. The invention contemplates the application of lacquer to an article by means of brushes, thereby minimizing the escape of fumes to a point where danger of explosion and fire is eliminated. The absence of fumes permits an article, lacquered by brushes to be immediately subjected to artificial drying without danger of fire and an object of the invention is the provision of a device through which articles such as tubes, or the like, may be continuously advanced and in turn subjected to cleaning, drying, lacquering and artificial drying without checking and stopping the article and without danger of fire or explosions.

Another object of the invention is the provision of an improved brushing and cleaning device adapted to thoroughly clean tubes, or the like, having embossed and otherwise irregular surfaces.

A further object of the invention is the provision of improved revolvable brush means adapted to apply lacquer evenly to articles having ir-

regular surfaces such as embossed and twisted tubing, or the like, with a minimum of loss of lacquer in the form of fumes.

Still another object of the invention is the provision of an improved device for feeding and advancing articles such as tubes, or the like.

A still further object of the invention is the provision of an improved recuperating air drying oven associated with means for circulating air through the oven and recirculating the same following its discharge upon a freshly lacquered surface without danger of igniting the fume laden air so circulated and recirculated.

A further object of the invention is the provision of an improved conveyor adapted to advance tubes or similar articles without marking or otherwise disfiguring the surface of such articles.

Still another object of the invention is the provision of improved means operable to automatically remove any surface lacquer and prevent any waste of lacquer so removed.

Still another object of the invention is to provide a cleaning and lacquering device of the kind described which is simple, compact, convenient and satisfactory for its intended purpose.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts,

Fig. 1 is a plan view of the cleaning and lacquering end of the device;

Fig. 2 is a plan view of the drying end of the device;

Fig. 3 is an elevational view of the disclosure shown in Fig. 1;

Fig. 4 is an elevational view of the heating device shown in Fig. 2;

10 Fig. 15 is a view along the line 15—15 of Fig. 13.

Referring now more particularly to the drawings the numeral 20 generally designates a duplex brushing unit. The numeral 21 generally designates a lacquering unit and the numeral 15 22 generally designates an automatic tube feeding device and recuperating air drying oven with recirculating air conduits. A tube 23 is shown diagrammatically in dotted lines as typical of an article to be advanced through the machine and 20 having in turn the steps of cleaning, drying, lacquering and cooling performed thereon.

The brushing unit 20 is carried by a supporting frame comprising longitudinal angle irons 24 and substantially vertical angle irons 25 serving 25 as legs. A pair of tanks 26, each normally containing a cleaning liquid substantially of the depth shown, are mounted on the supporting frame. An inwardly converging member 50, mounted on the front tank 26, serves as a guide by means of which the tube 23 may be manually 30 directed into the tank along the axis of an abrasive or brushing unit 39.

The tanks 26 are provided with a cover 27 and 35 are each equipped with one of the brushing units 39 for removing dirt or grease from the surface of the tube 23. Figs. 5 and 6 show the details of the brushing unit located in the end tank 26; the unit in the adjacent tank and its driving means are identical with that shown except that 40 the adjacent unit has its driving end adjacent to the driving end of the unit shown. Members 28 extending transversely of the tanks 26 provide supports upon which the brushing units 39 are 45 revolved by means hereinafter more particularly described. Legs 18 on the bottom of the members 28 provide spaces 19 permitting silt deposited by the brushing units to spread over the bottom of the tanks 26.

The brushing units 39 each consists of a cylindrical member 30 having closely fitting annular members 29 mounted on the ends. The members 50 29 have a groove fitting the curved upper bearing surface of the supporting members 28. The tight fit between members 29 and 30 cause these members to revolve together on the members 28 as a bearing. Clamp bars 24 fastened at each end by bolts 33 hold the brushing units seated on the members 28.

The cylindrical members 30 each have a plurality of equally spaced longitudinal slots 31 extending substantially their full length. The slots 55 31 are T shaped in cross section and provide seats for similar shaped members 35 forming a back in which a plurality of groups of radially extending bristles 36 are mounted. The members 35 and bristles 36 provide a plurality of elongated brushes, held in position in the slots 31 by bands 38. The bands 38 are easily removed for renewal or repair of the brushes. The bristles 36 stop short of intersection and thereby form an open space 40 extending the full length between the ends of the bristles. The dimensions of the space 40 are preferably slightly less than the lateral dimensions of the tube 23 which is advanced therethrough so that the ends of the

bristles 36 rub against the surface of the tube as the brushes are revolved. The tanks 26 are kept supplied with a cleaning liquid at approximately the level shown by the dotted line 17 to form a bath in which the bristles are partially submerged once during each revolution. The revolving bristles 36 are thereby covered to convey the liquid to the surface of the tube with which the brushes are in contact and the abrasion of the tube in the presence of the liquid substantially cleans the tubes. A plurality of apertures 37 are provided in the cylindrical member 30 to permit the free flow of liquid into and out of the member and the revolving bristles effectively clean tubes and like articles having embossed and warped surfaces.

The tube 23 upon emerging from the brushing unit 39 in the end tank 26 enters the adjoining tank 26 through a pipe 51 where it contacts with a brushing unit 39 similar to that located in the end tank. An inwardly converging member 52 mounted on the pipe 51 provides a guide directing the forward end of the tube 23 into the pipe. The substantially clean tube 23 is subjected to a second abrading and washing operation in the 100 adjoining tank and leaves the tank in a thoroughly cleaned condition.

The brushing units 39 are both actuated by being operatively connected with a motor 47 which is mounted on a support 46 over the front tank 26. A sprocket wheel 49, mounted on the motor shaft 48, is connected with a sprocket wheel 44 mounted on a shaft 42. The sprocket wheels 44 and 49 are connected by a sprocket chain 45. A pair of gears 32, only one of which is shown, 115 are mounted on the adjacent ends of the cylindrical members 30, and each operatively engage a pinion 43 mounted on the shaft 42. The brushing units 39 are thereby each simultaneously rotated by the motor 47 through the system of 115 sprockets, chains, gears and pinions as above described.

The tubes 23 having been subjected to two separate abrasion and washing operations leave the inner tank 26 through a pipe 53 upon the 120 end of which an air ring 107 is mounted. The detailed construction of the air ring 107 is shown in Figs. 11 and 12 in connection with the lacquering unit and consists of a ring 55 connected by pipes 56 with a supply of air under pressure. 125 The ring 55 has an annular shaped flange with which a hollow nozzle plug 57 has a threaded connection. The plug 57 is threaded into the flange of the ring 55 with its end spaced from the ring to provide an annular shaped aperture 130 58. The central portions of the ring 55 and the plug 57 have axially aligned apertures 108 and 109 respectively to provide a space through which the tube 23 travels. The peripheral edges of the openings in the ring 55 and the plug 57 are correspondingly beveled so that the central portion of the plug contacts with the corresponding beveled portion of the ring. A plurality of radially extending grooves 59 are formed on the beveled edge of the plug 57 through which air 140 is discharged from the annular aperture 58. The pipes 56 supply air under pressure to the aperture 58 from which it escapes through the grooves 59 in radially converging, rearwardly inclined streams against the surface of the advancing tube 23 and blows off the moisture through an opening 54 in the pipe 53 leaving the tube 23 thoroughly dried and cleaned.

The lacquering unit 21 is positioned in alignment with and adjacent the inner tank 26 and 150

consists of a tank 60 carried by a support comprising a pair of longitudinally extending angle irons 61 and a plurality of vertically extending angle irons 62. Lacquer is maintained in the tank 60 at substantially the level shown by the dotted line 16, the same being delivered into the main portion of the tank through a float box 63. The bottom of the float box 63 is connected with the main tank 60 by a plurality of apertures 64 in the side wall of the tank. A vertically extending supply pipe 65, connected with a source of supply, delivers lacquer into the float box 63 through a faucet 66. A float 67 operates the valve 70, by means of which the faucet 66 is opened and closed. The valve 70 is connected with the float 67 by a vertical rod 68 having one end fastened to the float and the other end pivotally connected with a lever 69. The valve 66 may be of any suitable type, but is shown as a flap valve mounted on the lever 69 so that as the float rises and falls with the lacquer, the valve is moved to closed and open position.

A guide member 50 is mounted in the end wall of the tank 60 adjacent the cleaning tanks 26 to receive the advancing tube 23. The opposite end wall of the tank 60 has a groove 100 which also serves as a guide for the tube 23 as it is advanced through the lacquering unit.

A pair of transversely extending partition members 71 are positioned in the tank 60 and on which is mounted a brushing unit 140 similar in construction and operation to the brushing units 39 already described. The brushing unit 140 comprises a cylindrical member 76 having relatively wide metal bands 73 mounted on each end. The bands 73 are journaled on the curved top surface of the partition members 71. Clamp bars 74, encircling the top portion of the bands 73, are fastened to the members 71 at one end by thumb screws 80 and at the other end by hinges 143. The bars 73 and the members 71 together provide a journaled mounting in which the cylindrical member 76 is rotatable. The member 76 has a plurality of longitudinally extending slots 77 in each of which a member 78 is mounted. The members 78 provide backs for brushes, each consisting of a plurality of groups of bristles 81. The backs 78 project inwardly a substantial distance and the bristles 81 are correspondingly short. It is desirable that the bristles be short to prevent bending under the weight of the lacquer and to permit the bristles to maintain a radial position.

The slots 77 and back members 78 are correspondingly offset, as shown, to provide seats for the members. Bands 75 at each end of the member 76 hold the members 78 seated in the slots.

The brushing unit 140 is operatively connected with a motor or other actuating mechanism (not shown) through a driving connection comprising a sprocket chain 87 rotating a sprocket wheel 86 fixedly mounted on a shaft 85. The actuating mechanism is supported by a bracket 82 fastened on the side of the tank 60 by any suitable means. The bracket 82 carries a bar 83 in which the shaft 85 is journaled. The bracket 82 also carries a bar 84, extending at right angles to the bearing 83, in which a shaft 104 is journaled. A pair of beveled gears 102 and 103 operatively connect the shaft 85 with the shaft 104. The shaft 104 is operatively connected with the cylindrical member 76 by a gear 105 so mounted on the shaft as to mesh with a gear 106 fixedly mounted on the cylindrical member. The described connections 75 are such that movement of the sprocket chain 87

causes the cylindrical member 76 to revolve in its mounting in the lacquer tank 60.

The cylindrical member 76 is removed from the tank 60 when not in use and placed in a bath of thinning liquid to prevent the lacquer from hardening and thereby rendering the bristles 81 unfit for use. The gear 105 is positioned in a lateral extension 144 of the tank 60. The gear 105 meshes with the gear 106 mounted on the end of the cylindrical member 76. The walls of the extension member 144 provide supports for bearings 145 in which the shaft 104 is journaled. The gear 106 is positioned at the same level or above the gear 105. By releasing the thumb screws 80, the clamp bars 74 may be turned about the hinges 143 and the cylindrical member 76, including the brushes, can then be removed from the tank as a unit and submerged in a thinning liquid and the brushes thereby be kept in condition without disassembly.

The inner ends of the oppositely positioned bristles 81 are spaced apart sufficiently to permit the tube 23 to be advanced therethrough with the bristles pressing against the surface of the tube. The bristles 81 are only partially submerged in the lacquer and in revolving they carry the lacquer to an elevation where it is spread uniformly over the surface of the tube 23. A plurality of longitudinally extending slots 79 are provided in the cylindrical member 76 between the slots 77 to permit the lacquer to flow into the interior of the member. The slots 79 converge inwardly a substantial amount and thereby function as buckets having constricted bottom openings serving to carry and pour the lacquer into the member 76 from above. The revolving of the member 76 also agitates the lacquer and keeps it of uniform consistency and quality. Slots 72 in the partition supports 71 are provided to maintain the lacquer at a uniform level in the tank 60.

The device is adapted for use with tubes and articles of different sizes and is constructed to avoid marking or disfiguring the freshly lacquered surfaces of the articles passing therethrough. The tubes 23 are automatically advanced by a feeding device mounted in the forward end of the tank 60. The feeding device comprises an upper inverted U shaped member 92 and a lower U shaped member 95. The member 95 is fixedly fastened to the side walls of the tank 60 by bolts 93 and 94. One end of the member 92 is pivotally mounted on the bolts 94 and a pair of tension springs 99 connect the other end of the member 92 with the member 95.

A pair of adjusting bolts 98 extend down through the side walls of the member 92 into contact with the upper edge of the member 95. The springs 99 constantly tend to hold the bolts 98 in contact with the member 95 and yield to permit limited rotation of the member 92 about its pivots 94 when subjected to strain.

Shafts 91 and 96 are mounted in the members 92 and 95, respectively, and each carries a V shaped or beveled roller 97 between which the tube 23 travels. The springs 91 normally hold the rollers 97 at a spacing determined by the position of the bolts 98. This spacing is slightly less than the lateral dimensions of the tube 23. The upper roller 97 is a driving roller and the lower roller is an idler. The tension of the springs 99 is sufficient that rotation of the upper driving roller 97 advances the tube.

The shaft 91, on which the upper driving roller 97 is fixedly mounted is operatively connected with the shaft 85 by a sprocket chain 89. A

sprocket wheel 90 mounted on the shaft 91 is connected by the chain 89 with a sprocket wheel 88 fixedly mounted on the shaft 85. The connection between the shaft 91 and 85 is such that the driving roller 97 is actuated by the mechanism that revolves the cylindrical member 76 and the tube 23 is automatically advanced at a rate corresponding to the rate of revolution of the cylindrical member 76.

10 A drip tank 101, adjacent the front end of the tank 60, is provided to receive any excess lacquer blown off the tube 23 by an air ring 55, which is connected with a supply of compressed air by a pair of tubes 56, the ring and tubes being similar to those used for drying the tube upon emergence from the cleaning tank.

The freshly lacquered tube is next advanced through a heating device to accelerate the drying of the lacquered surface. The heating device 20 consists in part of an inverted U shaped housing member 112 supported by a frame consisting of a pair of longitudinally extending angle irons 110 and a plurality of vertical angle irons 111. A horizontal diaphragm plate 113 extending the 25 full length of the housing member 112 provides an upper rectangular space through which an endless conveyor belt 114 moves to advance the tube 23. The belt 114 has a plurality of transversely extending rods 115, concave at their 30 middle portion to provide slats guiding the tube 23 through the middle of the housing. The belt 114 is actuated by a driving pulley 119, connected with power mechanism (not shown) by means of a belt 120. Pulley 119 is mounted on 35 a shaft 117 which also carries a pulley 116 with which the belt 114 cooperates. The return portion of the belt 114 moves underneath the housing and over an idler pulley 121. The shaft 117 is journaled in bearing blocks 118 mounted on 40 the angle irons 110. The belt 114 passes over pulleys similar in construction and mounting to the pulleys 119 and 121 positioned on the opposite ends of the angle irons 110 (not shown).

A pair of vertical screens 122, extend the 45 full length of the housing on either side of the belt 114. The screens 122 are connected with the upper wall of the housing member and with the horizontal diaphragm plate 113. The screens 122 permit air to flow freely therethrough and 50 serve as guides to keep irregular shaped articles on the belt 114 while passing through the housing member 112. An oven 123, mounted on the forward end of the housing member 112, is supported by a plurality of angle irons 124. The 55 oven 123 has a plurality of vertical tubes 129 terminating in upper and lower manifold plates 127 and extending through a plurality of baffle plates 128. The top wall of the oven has an opening 130 providing an outlet for fumes passing through the tubes 129. The oven is heated 60 by a burner 125 which is connected by a feed pipe 126 with a supply of gas (not shown). Air is circulated through the space 127 by means of a closed conduit system having its termini in the housing member 112 and so positioned that the air circulating through the conduit and heated by the oven 123 is discharged about and along the advancing tube 23. The side walls of the oven 123 and the manifold plates 127 have air tight joints preventing the escape of air from the space surrounding the tubes other than through the conduit system.

A hollow cylinder 133, closed at both ends, is positioned underneath the diaphragm plate 113 and between the angle irons 110. A pipe 132

forming a portion of the conduit system connects the cylinder 133 with the lower end of the oven 123. Pipes 136 and 137 also forming a portion of the conduit system connect the upper end of the oven 123 with the housing member 112. A fan 138, actuated by a motor 139, is positioned in the pipe 137. The fan draws air from the upper end of the oven and discharges it through the pipe 136 into one side of the housing member 112. The pipe 136 opens into the housing member at two points spaced apart a substantial distance and thereby circulates the air over a substantial length of the advancing tube 23. A portion of the air so delivered from the pipe 136 into the housing member 112 passes through the screens 122 and into direct contact with the tube 23, where it is cooled by drying the lacquer on the tube. The air thus cooled and laden with moist lacquer fumes is drawn by the action of the fan down through a plurality of apertures 135 in the diaphragm plate 113 into a chamber 142 through a plurality of apertures 135 in the diaphragm plate 113. The fume laden air is discharged from the chamber 142 into the cylinder 133 through a plurality of apertures 134 arranged in rows in the upper portion of the cylinder. The fumes and the moisture laden air in the cylinder 133 flow through the pipe 132 and is discharged into the bottom of the oven 123 where it is dried and reheated as it rises through the oven and again 105 flows through the pipe 137. The highly inflammable fume laden air is thus circulated and recirculated through the oven without danger of ignition or explosion and the tube 23 is thoroughly dried while being advanced through the housing member. The belt 114 conveying the tube 23 projects beyond the housing member a substantial distance to permit the tube to be cooled sufficiently that it can be handled upon its discharge from the belt.

Thus it will be seen that I have provided a device consisting of a novel duplex brushing unit operable to clean tubes and the like by abrasion and washing, in combination with novel means for advancing the tube or article being lacquered, 120 novel means for applying lacquer to the freshly cleaned advancing article, and novel means for accelerating the drying of the freshly lacquered article the latter comprising means for heating, 125 circulating and recirculating air over the article without danger of ignition of the fume laden air so circulated and recirculated.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a lacquering device, the combination of means for advancing an article through the device with means for applying lacquer to the 140 surface of the advancing article, and means for circulating heated air about the freshly lacquered surface of the advancing article to accelerate the drying of the lacquer, said lacquer applying means comprising a tank containing lacquer, 145 a cylindrical brush mounted in the tank with its axis positioned above and parallel to the surface of the lacquer, said brush having inwardly projecting radially extending bristles terminating short of intersection to provide a lon- 150

- gitudinal aperture through which the article to be lacquered is advanced, and means for revolving said brush about its axis to distribute lacquer uniformly over the surface of the article.
5. In a lacquering device, the combination of means for continuously advancing an article through the device, a lacquer tank through which said article advances above the lacquer level, a brush revolvable in the tank for applying lacquer to said article, said brush being cylindrical and having inwardly projecting radially extending bristles stopping short of intersection to provide a longitudinal aperture through which the article to be lacquered passes, means for revolving said brush, a housing through which the freshly lacquered article passes, a conduit connected with said housing, means for discharging air from said conduit over the lacquered surface of said article, and an oven associated with said conduit operable to heat the air so discharged.
6. In a lacquering device, the combination of means for continuously advancing the article through the device, a lacquer tank through which the advancing article passes, a brush revolvable in the tank for applying lacquer to said article, said brush being cylindrical and having inwardly projecting radially extending bristles stopping short of intersection to provide a longitudinal aperture through which the article to be lacquered passes, means for revolving said brush, a housing through which said freshly lacquered advancing article passes, a closed conduit connected with said housing, means operable to circulate the air contents of the housing through said conduit and to discharge the air over said article, and an oven associated with the conduit to heat the air passing through the conduit.
7. In a lacquering device, the combination of means for continuously advancing an article through the device, a lacquer tank through which the advancing article passes above the level of the lacquer, means for applying lacquer to said article while passing through the tank, said lacquer applying means comprising a cylindrical brush mounted in the tank with its axis positioned above and parallel to the surface of the lacquer, said brush having inwardly projecting radially extending bristles terminating short of intersection to provide a longitudinal aperture through which the article to be lacquered is advanced, and means for revolving said brush about its axis to provide a uniform coating of lacquer to the article, a housing through which the freshly lacquered advancing article passes, a closed conduit having its ends connected with said housing, means for circulating air through said conduit and discharging same around said article, and a fluid tight oven forming a portion of the conduit operable to heat the air passing through the conduit and around said article.
8. In combination, a tank containing cleaning liquid through which an article is adapted to be moved, means operable to simultaneously abrade and apply liquid to the surface of the article, a lacquering tank through which said article is advanced upon passing through said cleaning tank, means operable to apply lacquer uniformly over the surface of the article, said lacquer applying means comprising a cylindrical brush mounted in the lacquer tank with its axis positioned above and parallel to the surface of the lacquer, said brush having inwardly projecting radially extending bristles terminating short of intersection to provide a longitudinal aperture through which the article to be lacquered
- is advanced, means for revolving said brush about its axis to provide a uniform coating of lacquer on the article, a housing through which said freshly lacquered article travels, an oven, a closed conduit connecting the oven to said housing and means operable to circulate air through said conduit and oven and to discharge the air about the freshly lacquered surface of the article.
9. In combination, a tank containing cleaning liquid through which an article is adapted to be moved above the liquid level, revolving brush means partially submerged in the liquid, said brush means adapted to abrade and apply liquid to the surface of the article, a lacquering device through which said article passes upon emergence from the cleaning tank, said lacquering device consisting of means operable to continuously advance said article, a tank containing lacquer above which said article passes, means operable to apply lacquer uniformly over the surface of the article, said lacquer applying means comprising a cylindrical brush mounted in the tank with its axis positioned above and parallel to the surface of the lacquer, said brush having inwardly projecting radially extending bristles terminating short of intersection to provide a longitudinal aperture through which the article to be lacquered is advanced and means for revolving said brush about its axis to provide a uniform coating of lacquer to the article, a housing through which said freshly lacquered article travels, a fluid tight oven, a closed conduit connecting said oven and housing, and means operable to circulate air through said conduit and oven and to discharge the air in the housing about the freshly lacquered surface of the article.
10. In a lacquering device, the combination of means for continuously advancing an article through the device, a lacquer tank through which said article advances above the lacquer level, a brush revolvable in the tank for applying lacquer to said article, means operable to deliver air under pressure to the advancing article to remove excess lacquer therefrom, means for revolving said brush, a housing through which the freshly lacquered article passes, a conduit connected with said housing, means for discharging air from said conduit over the lacquered surface of said article, and an oven associated with said conduit operable to heat the air discharged from the conduit.
11. In a lacquering device, the combination of means for continuously advancing an article through the device, a lacquer tank through which said article advances above the lacquer level, a brush revolvable in the tank for applying lacquer to said article, said brush being cylindrical and having inwardly projecting radially extending bristles stopping short of intersection to provide a longitudinal aperture through which the article to be lacquered passes, means for revolving said brush, means operable to deliver air under pressure to the advancing article to remove excess lacquer therefrom, a conduit connected with said housing, means for discharging air from said conduit over the lacquered surface of said article, and an oven associated with said conduit operable to heat the air discharged from the conduit.
12. In a lacquering device, the combination of means for continuously advancing an article through the device, a lacquer tank through which said article advances above the lacquer level, a brush revolvable in the tank for applying lacquer to said article, said brush being cylindrical and having inwardly projecting radially extending bristles stopping short of intersection to provide a longitudinal aperture through which the article to be lacquered passes, means for revolving said brush, means operable to deliver air under pressure to the advancing article to remove excess lacquer therefrom, a conduit connected with said housing, means for discharging air from said conduit over the lacquered surface of said article, and an oven associated with said conduit operable to heat the air discharged from the conduit.
13. In combination, a tank containing cleaning liquid through which an article is adapted to be moved, means operable to simultaneously abrade and apply liquid to the surface of the article, a lacquering tank through which said article is advanced upon passing through said cleaning tank, means operable to apply lacquer uniformly over the surface of the article, said lacquer applying means comprising a cylindrical brush mounted in the lacquer tank with its axis positioned above and parallel to the surface of the lacquer, said brush having inwardly projecting radially extending bristles terminating short of intersection to provide a longitudinal aperture through which the article to be lacquered
14. In combination, a tank containing cleaning liquid through which an article is adapted to be moved, means operable to simultaneously abrade and apply liquid to the surface of the article, means operable to apply compressed air to the surface of the advancing article to dry

the same while in said tank, a lacquering tank through which said article is advanced upon passing through said cleaning tank, means operable to apply lacquer uniformly over the surface of the article, means operable to deliver air under pressure to the advancing article to remove excess lacquer therefrom, a housing through which said freshly lacquered article travels, an oven, a closed conduit connecting the oven with said housing, and means operable to circulate air through said conduit and oven and discharge the air about the freshly lacquered surface of the article.

10. In combination, a tank containing cleaning liquid through which an article is adapted to be moved, means operable to simultaneously abrade and apply liquid to the surface of the article, means operable to apply compressed air to the surface of the advancing article to dry the same, a lacquering tank through which said article is advanced upon passing through said cleaning

tank, means operable to apply lacquer uniformly over the surface of the article, said lacquer applying means comprising a cylindrical brush mounted in the lacquer tank with its axis positioned above and parallel to the surface of the lacquer, 80 said brush having inwardly projecting radially extending bristles terminating short of intersection to provide a longitudinal aperture through which the article to be lacquered is advanced, means for revolving said brush about its axis to provide a uniform coating of lacquer on the article, means operable to deliver air under pressure to the advancing article to remove excess lacquer therefrom, a housing through which said freshly lacquered article travels, an oven, 90 a closed conduit connecting the oven to said housing, and means operable to circulate air through said conduit and oven and to discharge the air about the freshly lacquered surface of the article. 95
